UNITED STATES PATENT OFFICE.

CHARLES A. SCHNEIDER, OF BRIDGEPORT, WISCONSIN.

CENTRIFUGAL MACHINE.

Application filed May 7, 1924. Serial No. 711,714.

This invention relates to machines in which materials in a container rotated at high speed are separated or treated, and it is adaptable for use in cream-separators and various other types of centrifugal liquid-separators, in centrifugal machines for separating solids from liquids, in centrifugal driers, and in other machines of the gyratory kind.

10 It is an object of the invention so to mount a rotor, for supporting a bowl or other container, that it automatically may balance and adjust itself and its load and rotate steadily and thereby compensate for changes in the center of gravity resulting from irregular 15 deposits of solid matter on walls or other unequal disposition of load.

Another object of the invention is to provide drive means for the rotor that will not interfere with automatic balancing or adjustment, the rotor and drive means being so formed and associated that the free gyration of each is permitted without disturbing the concentric relation of the other to fixed 25 parts.

Among other objects of the invention are so to form, coordinate, and associate the parts that there is a minimum of frictional resistance to operation of the machine; to 30 make the parts easy to disassemble for cleaning, repair, replacement, etc., and to provide adequate lubrication.

When considered in connection with the description herein, the characteristics of the 35 invention are apparent from the accompanying drawings, forming part hereof, wherein parts of a centrifugal machine of the cream-separator type are disclosed, for purposes of illustration.

40 Although the disclosures herein exemplify what now is considered to be a preferable embodiment of the invention, it is to be understood that it is not the intention to be limited necessarily thereto in interpretation 45 of the claims, as modifications and adaptations within the limits of the claims can be made without departing from the nature of the invention.

Like reference-characters refer to corresponding parts in the views of the drawings, 50 of which—

Fig. 1 is a bottom view of the rotor, with the retaining-ring removed;

Fig. 2 is a bottom view of the rotor with the retaining-ring in place; 55

Fig. 3 is a vertical section of the machine;

Fig. 4 is a vertical section of the rotor and of the upper portions of the spindle and drive-shaft;

Fig. 5 is a section on the line 5—5, Fig. 4; 60

Fig. 6 is a section of the drive-shaft and associated parts;

Fig. 7 is a vertical section illustrative of a modification; and

Fig. 8 is a view of the retaining-ring. 65

In the drawings, which disclose only such parts of the machine as are necessary for exemplification of the invention, A designates a base member and B, C, and D gear-case walls. 70

A vertical spindle and rotor-support 9 is mounted fixedly by having its lower end portion screw threaded and turned into a threaded opening in the base member A. The spindle may be adjusted upwardly and 75 downwardly by turning in the base member. The spindle is formed with a spiral lubricant groove 10 extending from the base to its top. It has in its upper end an inverted cone-shaped bearing-depression or seat 11. In order to avoid undue wear, the entire spindle or the upper portion thereof may be of hardened steel, or it may have in its upper end a hard insert 11^a, as shown by Fig. 4.

80 A ball or other suitable bearing 12 on the base member A has a drive element resting thereon. That element is of two separable parts. One of these parts includes a foot 13, which rests on the bearing, and a sleeve 14 integrally formed with a pinion 15. The sleeve is locked, by set-screws 16 or in any other suitable manner, to a tubular drive-shaft 17 therein, which is the other part of the drive element. The drive-shaft is rotatable on the fixed spindle, it extends to or 95 slightly beyond the upper end of the spindle,

and it has on its upper portion radially-extending projections or lugs 18.

A rotor 19, formed with a cavity 20 extending upwardly thereinto from its bottom, 5 has in its upper portion a concentrically-disposed pointed bearing member 21, of hardened steel or other suitable material. The bearing member rests in the terminal seat 11 of the spindle. The rotor-cavity is of sufficient size to permit the upper portion of the drive-shaft 17 to extend thereinto with considerable clearance between its wall and the shaft, in order that the rotor may be free to adjust itself automatically during rotation on the spindle. The rotor is formed with internal substantially vertical slots or recesses 22 extending upwardly thereinto from its bottom and open to the cavity, and into which the projections 18 of the drive-shaft extend and by which rotary motion is imparted to the rotor. In an annular seat 23 in the bottom of the rotor there is held by fastenings 24 a ring 25, which closes the lower ends of the slots 22 and by contact 20 with the projections 18 prevents the rotor from being lifted off from the drive-shaft. The ring has a depending outwardly-flaring annular flange 26.

If desired, the bearing-point and its seat 30 may be reversed; that is: the spindle may be equipped with a bearing point 21^a, and the rotor may have a depression or seat 11^b, as shown by Fig. 7.

The exterior contour of the rotor is such 35 as to permit a bowl or other container to be hung thereon and by frictional action to receive rotary motion therefrom. For example, there is shown by Fig. 3 a liquid-separator bowl 27 hung on the rotor.

40 Preferably, but not necessarily, the bearing-point should be above the center of gravity of the rotor, in order that the rotor may hang in freely balancing state on the fixed spindle, and the major portion of the container and its contents should be below the center of gravity for the same reason. However, the gravitational position of the bearing-point with respect to the rotor alone is immaterial, so long as the major 45 portion of the total weight of rotor, container, and contents of the latter is therebelow.

The projections 18 of the drive-shaft fit 50 loosely into the slots 22 of the rotor, so that no restraint is afforded thereby to the self-balancing of the rotor on its pivot-bearing, and the mass carried by that bearing, whether it be the rotor alone or the rotor, bowl, and the contents of the latter, is free at all 55 times to balance itself, both while in motion and at rest, without interference by the driving instrumentality.

Bolts or other suitable removable fasteners 58 hold on an upper wall B of the gear-case a casing 29, and the bowl 27 depends

into this casing. The drive-shaft is surrounded by an annular wall 30 spaced therefrom and extending upwardly from the bottom of the casing 29 and from an opening in the upper wall B to a point slightly above 70 the lower edge of the annular flange 26 of the ring 25. An annular extension 31 of the bottom of the casing 29 projects inwardly to a position in alignment with the upper end of the sleeve 14. That end of the sleeve 75 affords an annular shoulder. It is contactable with the annular extension 31, which constitutes a stop to prevent undue upward movement of the sleeve and the drive-shaft therein, as when the bowl is lifted off from 80 the rotor. The extension 31 also acts as an arrester-flange that prevents upward splash of lubricant into the space within the annular wall 30.

The drive-shaft and rotor, and thereby the 85 container on the latter, are driven at high speed by a gear 32 in mesh with the pinion 15, that gear being one of a train of gearing of the drive mechanism of the machine.

The gear-case contains lubricant, some of 90 which is worked up the spindle by the coaction of the rotating drive-shaft with the groove 10. Lubricant by that means is supplied to the pivot-bearing, it is thrown outwardly by centrifugal action against the inner wall of the rotor and into the slots 22, and it returns downwardly therefrom inside of the wall 30 to the gear-case and onto the pinion 15 and gear 32. The depending 95 flange 26, which extends downwardly inside of the wall 30, prevents any lubricant from being thrown outside of that wall into the casing in which the bowl rotates.

The parts of the machine may be disassembled easily for cleaning, repair, or replacement. After loosening the set-screws 16, the drive-shaft with the rotor thereon may be withdrawn upwardly from the spindle, and the rotor may be removed from the shaft after removal of the ring-fasteners 24. The sleeve 14 may be withdrawn upwardly 100 from the spindle after removal of the casing 29 with its sleeve-retaining flange 31. The spindle may be turned out of the base, 105 when it is necessary to remove it. The parts may be assembled in a manner substantially the reverse of that described for disassembly.

Having thus described my invention, what 110 I claim as new, and desire to secure by Letters Patent, is—

1. In a centrifugal machine, an upright fixed spindle, a cavitated rotor pivotally mounted on the upper end of said spindle 115 and having a slot extending upwardly thereinto, a tubular drive-shaft on said spindle, a projection extending from said shaft into said slot, and a removable closing member at the lower end of said slot.

2. In a centrifugal machine, an upright

fixed spindle, a cavitated rotor pivotally mounted on the upper end of said spindle having a slot extending upwardly thereinto and having also an annular seat in its bottom, a tubular drive-shaft on said spindle, a projection extending from said shaft into said slot, and a ring in said annular seat closing the lower end of said slot.

3. In a centrifugal machine, an upright

fixed spindle, a rotor on the upper portion of said spindle, a tubular drive-shaft on said spindle arranged to operate said rotor, a casing having a wall spaced from and disposed around said shaft, and an annular flange depending from said rotor into the space inclosed by said wall.

In testimony whereof I affix my signature.
CHARLES A. SCHNEIDER.
